United States Patent Office

Des. 192,248
Patented Feb. 20, 1962

192,248

GUN

Julius E. Brooks, Branford, Conn., assignor to Olin
Mathieson Chemical Corporation, a corporation of
Virginia

Filed Oct. 22, 1959, Ser. No. 58,026

Term of patent 14 years

(Cl. D30—1)

FIG - 2

FIG - 1

FIG - 4

FIG - 3

FIG. 1 is a side elevational view of a gun, on a reduced-scale, showing my new design;

FIG. 2 is a fragmentary side elevational view of the barrel portion of the gun;

FIG. 3 is a front elevational view of the muzzle end; and

FIG. 4 is a top plan view of the barrel portion.

The essential features of the design reside in the muzzle end portion shown in full lines.

I claim:

The ornamental design for a gun, as shown and described.
